DESIGN.

E. M. BEATTY.

BUTTON, BADGE, PIN, OR OTHER SIMILAR ARTICLE.

APPLICATION FILED SEPT. 16, 1918.

52,943.

Patented Feb. 4, 1919.

Inventor,

Elizabeth M. Beatty.

UNITED STATES PATENT OFFICE.

ELIZABETH M. BEATTY, OF WASHINGTON, DISTRICT OF COLUMBIA.

DESIGN FOR A BUTTON, BADGE, PIN, OR OTHER SIMILAR ARTICLE.

52,943.

Specification for Design.

Patented Feb. 4, 1919.

Application filed September 16, 1918. Serial No. 254,361. Term of patent 3½ years.

To all whom it may concern:

Be it known that I, ELIZABETH M. BEATTY, a citizen of the United States, residing at Washington, in the District of Columbia, have invented a new, original, and ornamental Design for Button, Badge, Pin, or other Similar Article, of which the following is a specification, reference being had to the accompanying drawing, forming part thereof.

The figure is a top plan view of the button, badge, pin or other similar article showing my new design.

I claim:

The ornamental design for a button, badge, pin, or other similar article, as shown.

ELIZABETH M. BEATTY.
